United States Patent Office

Des. 184,850
Patented Apr. 14, 1959

184,850

CHRISTMAS ORNAMENT OR SIMILAR ARTICLE

Jack Burnbaum, Newton, Mass., assignor to Bradford Novelty Co., Inc., Cambridge Mass., a corporation

Application March 19, 1958, Serial No. 50,100

Term of patent 14 years

(Cl. D29—1)

Fig. 1.

Fig. 2.

Fig. 3.

Fig. 1 is a front elevational view of a Christmas ornament showing my new design;
Fig. 2 is a side elevational view;
Fig. 3 is a top plan view thereof, and
Fig. 4 is a schematic sectional view taken on the line 4—4 of Fig. 1.

The back of the ornament is the same in appearance as the front.

I claim:

The ornamental design for a Christmas ornament or similar article, substantially as shown and described.
